DRAFT AND BUFFING GEAR

John H. Link, Merion, Pa., assignor to W. H. Miner, Inc., Chicago, Ill., a corporation of Delaware

Application July 9, 1937, Serial No. 152,773

4 Claims. (Cl. 213—9)

This invention relates to improvements in draft and buffing gears especially adapted for use in connection with mine cars.

One object of the invention is to provide a simple and efficient combined draft and buffing gear for mine cars so designed as to facilitate ready mounting of the gear on the end of the car.

A more specific object of the invention is to provide a gear of the character specified in the preceding paragraph including a buffing head and a draft element which are relatively movable and yieldingly resisted in their relative movement by shock absorbing means, together with readily attachable supporting means of simple design connecting the buffing head to the end of the car for holding the parts of the mechanism assembled and limiting outward movement of the buffing head.

Other objects of the invention will more clearly appear from the description and claims herein after following.

In the drawings forming a part of this specification, Figure 1 is a horizontal sectional view transversely of the end of a mine car, corresponding substantially to the offset line 1—1 of Figure 2, illustrating my improved combined draft and buffing gear in connection therewith, the gear being shown partly in top plan and partly in horizontal section on said line 1—1. Figure 2 is a part front elevational view and part vertical sectional view of the structure illustrated in Figure 1, corresponding substantially to the offset line 2—2 of Figure 1. Figures 3 and 4 are vertical sectional views, corresponding respectively to the lines 3—3 and 4—4 of Figure 2. Figure 5 is a view similar to Figure 1, illustrating the manner of attaching the combined draft and buffing mechanism to the end of the car, the attaching lug or bracket at the right hand side of the mechanism being shown in one position in dotted lines and in another position in full lines, the dotted line position corresponding to that shown in Figure 1 and the full line position showing the lug or bracket swung to one side to facilitate application of the buffing head.

In said drawings, 10 indicates the vertical end wall of a mine car and 11 the floor of the car, which, as is the usual practice, is depressed at the central portion of the car, as indicated at 12. The end wall 10 is provided with an outwardly extending horizontal bottom flange 13, which is spaced above the bottom wall of the depressed floor section 12 and is cut away at the center, as indicated at 113. As shown most clearly in Figures 3 and 4, the floor section 12 has an upstand-

ing vertical flange 14 at its outer end parallel to the wall 10 and slightly to the rear of the latter. A transversely extending channel member 15 is disposed between the projecting flange portion 13 of the wall 10 and a bottom plate 16 secured to and projecting outwardly from the depressed floor section 12. The channel member 15 is, in effect, an end sill member. This channel member 15 has the web thereof disposed vertically and the top and bottom flanges projecting outwardly 10 as clearly shown in Figures 3 and 4. The top and bottom flanges of the channel member 15, respectively, abut the underneath side of the flange 13 of the end wall 10 of the car and the top side of the plate 16 and are secured thereto in 15 any suitable manner, preferably by rivets, as shown. The vertical web of the channel member abuts the outer face of the upturned flange 14 of the floor section 12. At the opposite ends, the vertical web of the channel member is provided 20 with rearwardly extending flanges 17—17, as shown in Figures 1 and 5, which are secured to upstanding side flanges 18—18 of the floor section 12.

In carrying out my invention, I mount the 25 parts of the combined gear between the top and bottom flanges of the channel member 15, said channel member thus forming a partial housing for the mechanism. My improved mechanism proper comprises broadly a buffing head A; a 30 draft member B; combined supporting and guide brackets or lugs C—C; two cushioning springs D—D; and a coupling pin E.

The buffing head A is in the form of a hollow member having spaced horizontal top and bottom 35 walls 19—19, spaced vertical side walls 20—20, and a transverse front wall 21. The front wall 21 presents an outer curved buffing surface, as clearly shown in Figure 1. The bottom wall 19 is provided with a central opening 22 adapted to 40 accommodate the bottom end of the pin E. The top wall 19 of the buffing head A is provided with a central opening 23, which is somewhat longer than the opening 22, as clearly shown in Figure 3. The opening 23 is of such a length as to permit the necessary swinging movement of the pin 45 E to actuate the draft member during the draft action of the gear. Near the opposite ends, the front wall 21 of the buffing head A is provided with interior spring seats 24 having central bosses 50 25, which serve to center the springs. At the rear of the buffing head A, the side walls 20—20 thereof are provided with laterally inturned flanges 26—26 which form retaining and stop shoulders, as hereinafter pointed out.

- The draft member B is in the form of a casting or forging having a vertical transverse rear section 21 and a forwardly extending central yoke member 28 formed integral with said section 21.
5. The section 27 has spring seats 29—29 at opposite sides thereof on which the inner ends of the springs D—D are seated. As clearly shown in Figures 1 and 2, the springs D—D are two in number and are disposed at opposite sides of the 10 yoke section 28 of the draft member B. The front ends of the springs D—D engage the spring seats 24—24 of the buffering head A and are held in centered position by the bosses 25—25, which engage within the coils of the springs. The yoke 15 section 28 of the draft member B is closed at both ends, as shown in Figures 1, 3, and 5, and is of the vertical section shown in Figure 3. The rear end portion of the yoke section 28 is provided with top and bottom walls 30—30, as 20 clearly shown in Figure 3, thereby providing top and bottom openings 31—31 at the forward end thereof, which extend from one side wall to the other of the yoke. The top opening 31 is of greater size lengthwise of the yoke than the bottom opening 31 and has the front wall thereof inclined outwardly, as indicated at 32, to accommodate the coupling pin for swinging movement. The front wall of the yoke is cut away near the bottom, as indicated at 33, said cut 25 away portion forming a continuation of the bottom opening 31 and accommodating the lower end of the coupling pin E in its swinging movements. As shown in Figure 2, the forward end of the yoke is normally spaced inwardly from the transverse front wall 21 of the buffering head A so as to permit of the necessary rearward movement of the buffering head during a buffering action of the gear. The inner end portion of the draft member B, as clearly shown in Figure 4, is arranged between the top and bottom flanges of the channel member 15 and is thus supported by the channel member.
- The combined guide and supporting brackets or lugs C—C are disposed at opposite sides of 45 the mechanism and serve to support and guide the buffering head A and also limit its outward movement. Each bracket C is of L-shaped form in plan, as clearly shown in Figures 1 and 5. Each bracket C has a forwardly projecting guide 50 arm 34 which extends into the buffering head A between the top and bottom walls 19—19 thereof. The arm 34 comprises top and bottom horizontal platelike sections 35—35 connected by a vertical web 36. At the inner end of the arm 34, the bracket C is provided with spaced top and 55 bottom securing flanges 37—37 which form continuations of the platelike sections 35—35 of said arm. As shown in Figures 1 and 2, the flanges 37—37 fit between the top and bottom flanges of the channel member 15 and are secured thereto by rivets. The arm portions 34—34 of the L-shaped brackets C—C project from the channel member 15 at right angles to the length of the latter. Each arm 34 is provided with a 60 laterally projecting stop shoulder 38 thereon which is in the form of a vertically disposed rib on the outer side of the web 36 of said arm. The stop shoulders of the two arms overhang the two inturned flanges 26—26 of the buffering head A and thus limit outward movement of the latter. The buffering head is thus securely anchored to the end sill of the car and supports the draft member B over which it is telescoped. As shown clearly in Figures 1 and 5, the top 65 and bottom platelike sections 35—35 and 35—35

of the arms 34—34 of the brackets C—C are cut away on the outer sides of said arms rearwardly of the stop ribs 38—38 to accommodate the inwardly projecting flange portions 26—26 of the buffering head A. Each flange 37 of each 5 bracket C is preferably provided with two rivet receiving openings 39—39, said openings being located as indicated in Figures 1 and 5 and receiving the securing rivets 40—40 which also extend through suitable openings in the top and bottom flanges of the channel member 15. The rivet openings 39—39 and 39—39 of the top and bottom flanges 37—37 are preferably in vertical alignment.

The coupling pin E comprises a substantially 15 cylindrical shank portion having an annular flange 41 at its slower end and threaded at its upper end. The pin E extends through the openings of the buffering head A and the draft member B and through the opening of the usual 20 coupling link, which is indicated at 42, and serves to couple one car to another. The threaded upper end portion of the pin E projects above said link 42 to receive the nut 43. The nut 43 serves to prevent dropping of the pin through 25 the opening of the link 42. The nut is preferably locked against accidental removal in a well-known manner by a cotter pin 44 extending through the extremity of the threaded portion 30 of said pin. The head 41 at the lower end of 35 said pin by engagement with the bottom wall of the buffering head prevents accidental removal of the pin in an upward direction. The pin E forms, in effect, a lever by which the draft member B is pulled outwardly during a draft action. 40 The pin E has a loose fit within the openings of the buffering head A and the draft member B whereby the pin is free to counterbalance the link 42 and maintain the same in horizontal position to facilitate coupling with an adjacent car. As will be evident, the nut 43 of the pin E, which, in effect, serves as a head of said pin, has shouldered engagement with the upper face of the link, whereby the downward pull exerted through the weight of the pin holds the link 42 45 in said horizontal position. Sagging of the link is thus completely avoided which is an important consideration inasmuch as trainmen are required to adjust sagging or drooping links, which is a hazardous operation. As will be understood 50 both ends of each car are similarly equipped with this arrangement of weighted coupling pin, and when two adjacent cars are coupled the link extends between the same and is connected to each car by a pin. When the cars are uncoupled, the 55 pin at one end of the link only is removed, the other pin remaining in position on its car. This last named pin thus maintains the link in horizontal position for coupling operations.

My improved combined draft and buffering gears are preferably assembled complete before shipment and application to cars. In assembling the draft member B, the springs D—D, and the buffering head A, the buffering head is telescoped over the forwardly projecting portions of the draft member and springs which have been previously placed in position on the draft member, as shown in Figures 1, 3, and 4. The pin E is then applied through the openings of the draft member B and the head A, thereby anchoring the 60 parts together. To apply the pin, the same is inserted in an upward direction through the openings of the buffering head and draft member and locked against removal by the nut 43 and cooperating cotter pin 44. The parts thus as- 65

sembled form a complete unit for shipment and application to the car. In mounting the gear unit on the car, one of the brackets or lugs C is first riveted in fixed position on the end sill formed by the channel member 15. As shown in the drawings in Figures 1 and 5, the left hand bracket C is the one so fixedly riveted. The right hand bracket C is then secured to the bottom flange of the channel member 15 by a pin or bolt 45 as shown in full lines in Figure 5, the bolt being loosely engaged through the left hand opening of said bracket, which opening is laterally offset with respect to the vertical plane of the arm 34 thereby permitting swinging movement of said bracket on said pin or bolt as a pivot from the full line position of said bracket in Figure 5 to the dotted line position in Figure 5 or the full line position in Figure 1. The assembled gear comprising draft member, springs, buffing head A, and pin E, is then applied to the car, as shown in Figure 5, the flange 26 at the left hand end of the head A, as seen in Figure 1, being brought into hooked engagement with the shoulder 38 of the rigidly secured bracket C. As will be evident, with the left hand bracket C in the full line position shown in Figure 5, the flange 26 at the right hand side of the buffing head A readily clears the stop shoulder 38 of said bracket, and the head A may be positioned, as shown in said figure. While the head A is held in position, the bracket C is swung from the full to the dotted line position, thereby bringing the stop shoulder 38 of said bracket into operative engaging relation with the inturned flange 26 at the corresponding side of the buffing head A. The bracket C is then riveted to the flanges of the channel member 15 by first fastening the securing rivets through the openings which are unoccupied and then removing the bolt 45 and fastening a securing rivet through the openings from which said bolt has been removed.

Although the procedure just described of applying the gear to the car is the preferable one, the gear may also be applied by assembling the draft member, coupling pin, and springs with the buffing head, as hereinbefore described, and then placing the brackets C—C in position within the buffing head with the shoulders 38—38 of the arms 34—34 of said brackets in hooked or overhanging engagement with the flanges 26—26 of the buffing head A and finally placing the parts in the applied position shown in Figure 1 and riveting the brackets C—C to the flanges of the channel member 15.

As will be obvious, the pin E may be readily removed and reapplied after the gear is fixed on the end of the car. To remove the pin, the same is withdrawn in a downward direction after disengaging the nut 43 from the upper threaded end of said pin. It is evident that the pin may be reversely arranged, if desired, that is, with the flange 41 at the top. This arrangement is used in case it is found desirable to apply the pin from above and withdraw the same in an upward direction.

The operation of my improved draft and buffing gear is as follows: When the buffing head A is moved inwardly toward the car, the springs D—D are directly compressed against the rear section 27 of the draft member B, the draft member, at this time, being held stationary by engagement with the vertical web of the channel member 15. Rearward movement of the buffing head will be limited by engagement with the front end edges of the flanges of the channel

member or end sill member 15. When a pulling force is applied to the coupling link in draft, the upper end of the pin E, which, in effect, forms a lever, is moved outwardly away from the car, the lower end of the pin rocking on the bearing face formed by the rear wall of the bottom opening 22 of the buffing head A. Inasmuch as the inward movement of the buffing head is resisted by the springs D—D, the lever action of the pin E will pull the yoke outwardly away from the end of the car, thereby compressing the springs D—D against the buffing head. During this action the buffing head A is held against outward movement by the stop brackets C—C, the stop shoulders of which are, at this time, in engagement with the flanges 26—26 of the head A. Outward movement of the draft member with respect to the buffing head A will be limited by engagement of the front end of the draft member with the front wall of the buffing head A.

I have herein shown and described what I now consider the preferred manner of carrying out my invention, but the same is merely illustrative and I contemplate all changes and modifications that come within the scope of the claims appended hereto.

I claim:

1. In a combined draft and buffing gear for mine cars, the combination with an inwardly movable buffing cap on one end of the car, said cap having transverse interior stop shoulders at opposite sides; of an outwardly movable draft member; cushioning means interposed between said buffing head and draft member; and means for anchoring said cap to the end of the car including separate supporting brackets at opposite sides of the buffing cap, each bracket having a base portion and an outstanding arm provided with a transverse, laterally projecting flange adapted to overhang the corresponding interior shoulder, said base portion being rigidly fixed to said end of the car by vertically disposed, laterally spaced securing elements extending through said base portion, said base portion being swingable about the vertical axis of one of said securing elements, to a required extent, prior to being fixed by all of said securing elements to clear said flange from overhanging relation to said interior shoulder, clearance being provided within said cap to permit swinging movement to said required extent.

2. In a combined draft and buffing gear for cars, the combination with an outwardly movable draft member at the end of the car; of a hollow buffing head telescoped over said draft member, said head having laterally inwardly directed stop flanges at opposite sides thereof; spring means interposed between said draft member and head; L-shaped retaining brackets, each having an arm mounted on the car and a second arm at right angles thereto, said last named arm of each bracket projecting outwardly from the end of the car and having a laterally extending stop shoulder overhanging the stop flange at the corresponding side of said head, removable temporary attaching means for one of said brackets, extending through said first named arm for swingily supporting the same for movement about a vertical axis, the second named arm of said bracket being spaced from the corresponding spring means to provide clearance to permit swinging of said bracket to one side to position said second named arm to clear the stop shoulder thereof from the corresponding stop flange; and rivet members engageable through

said first named arms of said brackets, for rigidly securing said brackets to the car.

3. In a combined draft and buffing gear for cars, the combination with a hollow buffing cap mounted for movement inwardly of the end of the car, said head having inwardly facing shoulders at opposite ends thereof; of means for anchoring said cap to the end of the car and limiting outward movement thereof, comprising a pair 10 of laterally spaced L-shaped brackets, each having one arm extending transversely of the end of the car and the other arm thereof outstanding from said end of the car and having a shoulder in overhanging engagement with the corresponding 15 shoulder of said cap, each of said brackets having the transversely disposed arm thereof anchored to the end of the car by a securing element extending through said last named arm and on which said bracket may be swung to clear 20 the shouldered end thereof from the shoulder of said cap, clearance being provided within said cap for permitting the required swinging movement of said brackets; and means for securing said arm against swinging movement.

4. In a combined draft and buffing gear for cars, the combination with a hollow buffing cap mounted on the end of the car, said cap having interior laterally inwardly directed stop flanges at opposite sides thereof; of a pair of spaced 5 supporting brackets secured to the end of the car, each bracket having an outstanding arm having a stop shoulder thereon overhanging the stop flange at the corresponding side of the buffing cap; a vertically disposed pinlike securing 10 element extending through said bracket, said pinlike element being offset laterally inwardly from a longitudinal vertical plane coincident with the inner edge of the corresponding stop flange of said cap, and fixed to the end of the car, clearance being provided within said cap to permit the required swinging movement of said bracket; additional securing means spaced from said securing element, extending through said bracket and fixed to the car for holding said bracket 15 against swinging movement about the axis of the pinlike element.

JOHN H. LINK.
